UNITED STATES PATENT OFFICE.

FAUSTO PEDREIRA MACHADO, OF NEW YORK, N. Y.

TURBINE-ENGINE.

1,360,305.

Specification of Letters Patent. Patented Nov. 30, 1920.

Application filed August 19, 1918. Serial No. 250,427.

To all whom it may concern:

Be it known that I, FAUSTO PEDREIRA MACHADO, a citizen of the United States of Brazil, residing at 65 West 52nd street, city, county, and State of New York, have invented new and useful Improvements in Turbine-Engines, of which the following is a specification.

My invention relates to turbine engines and more particularly to turbines having steam as a motive agent, although it is to be understood that other motive agents can be employed with equal success.

An object of my invention is to provide a reversible turbine which utilizes the pressure, the expansion, and the velocity of the steam in both directions.

Another object of my invention is the provision of a reversible turbine of the class described, which is economical, simple in construction, and of maximum efficiency.

A further object of my invention is the provision of means for controlling a plurality of reversible turbines, and means associated therewith for automatically controlling the inlet and exhaust nozzles of each turbine.

I will describe three forms of turbines and one controlling means for a plurality of turbines, all embodying my invention, and will then point out the novel features thereof in the claims.

In the accompanying drawings, Figure 1 is a view in vertical transverse section taken on the line I—I of Fig. 2 and looking in the direction of the arrows, showing one form of turbine embodying my invention;

Fig. 2 is a vertical, longitudinal sectional view taken on the line II—II of Fig. 1, and looking in the direction of the arrows;

Fig. 3 is a fragmentary detail view of the controlling means for the turbine shown in Figs. 1 and 2;

Fig. 4 is a fragmentary, sectional view of the controlling means for the turbine shown in Figs. 1 and 2;

Fig. 5 is a fragmentary view showing, in perspective, one form of vane and lubricating roller-bearing embodying my invention;

Fig. 6 shows fragmentary, perspective views of three forms of modified vanes embodying my invention;

Fig. 7 is a vertical, transverse, sectional view taken on the line VII—VII of Fig. 11, looking in the direction of the arrows, show-

ing a modified form of turbine embodying my invention;

Fig. 8 is a view showing in side elevation one form of controlling means for a plurality of turbines embodying my invention; 60

Fig. 9 is a view showing in top plan the controlling means shown in Fig. 8;

Fig. 10 is a view showing in end elevation, and partly in section, the controlling means shown in Figs. 8 and 9; 65

Fig. 11 is a vertical, longitudinal, sectional view of the modified form of turbine, taken on the line XI—XI of Fig. 7;

Fig. 12 is a view similar to Fig. 11, taken on the line XII—XII of Fig. 7; and 70

Fig. 13 is a view showing in vertical, transverse section another form of turbine embodying my invention.

Similar reference characters refer to similar parts in each of the several views. 75

Referring to the drawings, and more particularly to Figs. 1 and 2, A designates generally a single turbine engine comprising a stator S and a rotor R within the stator. The stator S, as shown in Fig. 1, is mounted upon a suitable base B and comprises a pair of spaced side plates 10 and 10^a which are curved in opposite directions at their marginal edges to provide annular distributing channels 11 and 11^a, respectively. As clearly shown in Fig. 2, the distributing channels 11 and 11^a are of U-shaped formation in cross-section and have their open sides arranged in confronting relation to each other. Spanning the open sides of the distributing channels 11 and 11^a are rings 12 and 12^a, respectively, which are substantially T-shaped in cross-section and have their flanged ends resting upon the periphery of the side plates 10 and 10^a, as shown in Fig. 2. Interposed and spanning the space between the rings 12 and 12^a is an annulus 13 which is formed with transversely extending steam chests 14 and 14^a, communicating with steam nozzles 15 and 15^a, respectively. The steam chests 14 and 14^a in turn communicate respectively with the distributing channels 11 and 11^a through inlet ports 16 and 16^a, respectively, formed in the rings 12 and 12^a. Because of the sectional line in Fig. 1, from which the sectional view of Fig. 2 is taken, the ports 16^a do not appear, but it is to be understood that the ring 12^a is formed with ports identical to the ports 16. The ports 16 and 16^a are controlled by valves 17 and 17^a, having 110

stems 18, which are threadedly mounted in bosses 19 and which extend exteriorly of the stator S and are provided with wheels 20 operated by handles 21. It will be obvious from this arrangement that the valves 17 and 17^a are opened or closed, according as the stems 18 are rotated in one direction or the other.

As shown, the steam chests 14 and 14^a are 10 circular in cross section and are substantially coextensive in width with the annulus 13. The nozzles 15 and 15^a are, as shown in Fig. 2, of rectangular formation in cross-section, and are tapered from their inlet ends to 15 their outlet ends. The nozzles 15 are arranged to drive the rotor R in one direction, while the nozzles 15^a are arranged to drive the rotor R in the opposite direction, and all of the nozzles are adapted to be arranged 20 at an angle which is most advantageous for securing the maximum energy from the steam. At diametrically opposite points on the annulus 13, and between each pair of nozzles 15 and 15^a, the annulus is formed 25 with exhaust ports E and E'. Each exhaust port E and E' communicates with the rotor R and is provided with a horizontal bore, the inner end of which is rounded, as shown.

As shown in Figs. 1 and 3, the top of the 30 stator S is provided with a steam supply pipe 22, which communicates with pipes 23 and 23^a connected to the distributing channels 11 and 11^a, respectively. At the intersection of the pipes 22, 23, and 23^a, I provide a controlling cock 24 operated by a handle 25, which, as shown in Fig. 4, is a three-way cock. The ports in the cock 24 are so arranged that when the cock occupies the normal position as shown in Fig. 40 3, the supply pipe 22 is disconnected from the pipes 23 and 23^a. When the cock 24 is moved to the extreme right-hand position, communication is established between the pipes 22 and 23, and when moved to the extreme left-hand position, communication is 45 established between the pipes 23^a and 22.

As shown in Fig. 2, the side plates 10 and 10^a are provided with axial openings in 50 which is journaled a shaft 26, suitable bearings being provided therefor to reduce the friction. Rigidly secured to the shaft 26 is the rotor R, and as here shown such rotor comprises a plurality of segmental sections 27, secured together in disc formation, the 55 peripheries of which are formed with flanges 28 to which is secured an annulus 29. The annulus 29 is relatively wide and is internally threaded at its marginal edges to receive the threaded portions of rings 30, 60 such rings being of L-shaped formation in cross-section, and having their outer edges contacting with the inner edges of the rings 12 and 12^a. To form a steam-tight fit between the rotor R and the stator S, the side

plates 10 and 10^a are formed with circular 65 recesses 31 for snugly receiving the rings 30.

Referring again to Fig. 1, V indicates an outer series of vanes and V' an inner series of vanes. The vanes V' are disposed radially of the rotor R, are formed on the periphery 70 of the annulus 29, are substantially coextensive in width with the annulus, and are spaced apart by arcuate grooves 32. The outer vanes V are secured to the rings 30 and span the space therebetween as shown 75 in Fig. 2. As shown in Fig. 5, each vane V comprises a linear blade 33 and an arcuate blade 34 disposed adjacent the base of the vane and spaced apart a portion of its width to receive a lubricating roller bearing 35. Each roller bearing 35 is coextensive in 80 length with the width of the annulus 13, the rings 30 being formed with recesses (not shown), for receiving the ends of the roller bearing, it being understood that the ends of the roller rest upon the inner edges of the rings 12 and 12^a, so that when passing the nozzles 15 and 15^a they will not leave the rings 30. The roller bearing 35 is of any 85 suitable type and, as shown in Fig. 5, is of cylindrical formation to receive a lubricant, and is perforated to permit the lubricant to seep out of the cylinder and into contact with the inner periphery of the annulus 13. By this arrangement, the roller bearings 35 90 materially reduce the friction between the rotor and the stator, and also form a steam-tight fit to prevent leakage between the rotor and stator, which is found in most turbines. It will be understood, of course, that suitable means will be provided for replenishing 95 the supply of lubricant to the rollers. This may readily be accomplished, for instance, by providing an opening through the side plates 10 and 10^a in alignment at some point 100 in the circular path of the rollers, and which opening may be closed by a suitable cap or plug. It has not been deemed necessary to 105 illustrate these openings herein, since it would seem to be such a simple and obvious 110 matter.

As clearly shown in Fig. 1, the vanes V are arranged between the vanes V' to form a series of transversely extending throats or passageways for causing the steam to 115 take a sinuous or zig-zag course throughout the circumference of the rotor, as will be hereinafter described.

The operation of the turbine A is as follows:

With the valve 24 in the position shown in Fig. 4, steam from the supply pipe 22 is admitted to the distributing channel 11 through pipe 23. The steam now traverses the distributing channel 11, and with the valves 17 125 in the open position, as shown in Fig. 2, steam is admitted to the steam chests 14 through ports 16. The steam passes from

the chests 14 into the nozzles 15 where it impacts against the vane V to cause rotation of the rotor R. By virtue of the distributing channels 11 and valves 17, the velocity with which the steam enters the chests 14 is readily controlled, and this control of the velocity of the steam permits the speed of the rotor to be varied at will. Steam, upon entering chests 14, is distributed uniformly over substantially the entire width of the rotor R before reaching the nozzles 15, and the nozzles 15 being of a corresponding width, the jets of steam emanating therefrom are caused to impact against the vanes of the rotor throughout their entire lengths. In this manner a very efficient turbine engine is obtained, because the steam, being in contact with the vanes throughout their entire lengths, exerts its entire force upon such vanes at the most advantageous angle; and, further, because the steam is caused to expand in the nozzle itself before it reaches the vanes of the rotor R, thus materially aiding in the utilization of the entire expansive force of the steam.

As the steam leaves the nozzle 15, it impacts against the linear blade 33 of each vane V, and then passes to the arcuate groove 32 next in advance, and because of the shape of such groove, the steam is deflected against the vane V' next in advance. It then strikes the next vane V, and so continues until it exhausts out of the ports E or E'. It will thus be seen that the steam describes a sinuous or zig-zag path during its travel from one nozzle to its corresponding exhaust port, so that the expansion as well as the velocity of the steam is utilized to produce a turbine of high efficiency. The nozzles 15 are employed only when it is desired to rotate the turbine forward. However, when it is desired to reverse the movement of the turbine, the nozzles 15^a are employed, so that the steam impinges upon the rotor R in the reverse direction, as will be understood. During the reverse movement of the rotor R, the steam from nozzles 15^a first impacts against the curved blade 34, sliding off such blade, and then striking the linear blade 33, so that the steam again describes a zig-zag or sinuous path and thus completely utilizes the kinetic energy of the steam.

With the rotor R rotating continuously in one direction or the other, the roller bearings 35 are caused, by virtue of centrifugal force, to move radially within the vanes V so that they constantly bear against the inner surface of the annulus 13, irrespective of any irregularities in the surface thereof or any diametric play of the rotor; wherefore, a steam-tight fit is constantly maintained between the rotor R and the stator S. During rotation of the rotor R, each roller bearing 35 is also caused to rapidly rotate, thus throwing out the lubricant contained

therein and thoroughly lubricating the surfaces of the rotor and stator.

One of the important features of my invention is the fact that, because of the particular arrangement of the nozzles 15 and 15^a and the formation and arrangement of the vanes V and V', I produce a turbine which is truly reversible and which develops substantially the same power in one direction as it does in the other. Another important feature of my invention is the provision of the distributing channels 11 and 11^a, and the means for controlling the velocity of the steam from the distributing channels to the steam chests 14.

In Fig. 6 I have shown three modified forms of vanes V for use in conjunction with the rotor R. In Fig. 6^a, the vane V is of U-shaped formation and its open side is adapted to be disposed outwardly of the rotor, so that its upper edge is disposed between the vanes V'. The form shown in Fig. 6^b is provided with a longitudinally extending groove 37, in which is disposed a lubricating roller bearing 35. In Fig. 6^c, I have shown an articulated vane V, which comprises a base bar 39 of U-shaped formation, and a vane portion 38, which is adjustably secured to the base bar by means of a pin 40 to allow vertical adjustment of the vane portion on the base and to thus effect a steam-tight fit between the rotor and stator.

Referring now to Figs. 7, 11, and 12, I have here shown a modified form of turbine, indicated generally at A'. This turbine comprises a stator S', which is identical to the stator S in the first form of my invention, with the exception that the annulus 13 is provided with re-injection chambers C which communicate with the interior of the stator S' and which coact with other re-injection chambers C' formed on the confronting sides of the side plates 10 and 10^a to provide two pairs of serpentine channels. Each pair of channels extend from a point on the stator S' adjacent the nozzles 15 to a point in advance of one of the nozzles 15^a. As shown in Fig. 7, each channel is tapered in cross-section from the inlet to the outlet end to provide serpentine channels of progressively increasing dimensions, for purposes which will be hereinafter described. The chambers C are formed integral with the annulus 13, while the chambers C' are formed with spaced plates 50 and 50^a secured to the inner faces of the side plates 10 and 10^a. The plate 50 of each chamber is provided with a flange 51 which connects the two plates and forms the inner side wall of the chamber, as shown in Fig. 11.

The rotor R' differs from the rotor R of Fig. 1, in that the wheel portion thereof is cast integral, instead of in sections, and the annulus 29, which is cast integral with the wheel portion, is formed with openings 52

to effect communication between chambers C and chambers C'.

In this embodiment of my invention, the rotor is provided with three sets of vanes, indicated at V', V² and V³, respectively. The vanes V' are identical to the vanes V' of the turbine A, and the vanes V² correspond to the vanes V of the turbine A, but are arranged opposite to the vanes V' and 10 have both sides curved in the form of an arc so as to offer the least resistance to the steam. These vanes V² are also formed with grooves 37 to receive the roller bearings 35. The vanes V³ are tapered transversely from their 15 outer edges to their inner edges and are interposed between the vanes V' and V² and in alternate relation thereto. By this arrangement of vanes, three series of transversely extending throats or passageways 20 53, 54, and 55, respectively, are provided. The throats 53 and 54 are opposite to each other and are formed by the vanes V' and V² in combination with vanes V³, while the throats 55 are disposed between each pair 25 of throats 53 and 54 and are formed by the coaction of all of the vanes.

The operation of the turbine A' is as follows:

With the valve 17^a controlling the nozzles 30 15^a open, and the valves 17 controlling the nozzles 15 closed, steam leaves the nozzles 15^a and, passing to the vanes V and V', impacts against said vanes and then expands radially in opposite directions. It then 35 passes through the throats 53 and 54, and impacts against the vanes V³ until it reaches the reinjection chamber C, which constitutes the smaller ends of the serpentine channels. The course of the steam is clearly indicated 40 by arrows in Fig. 7. A portion of the steam enters said chamber C and the remaining steam continues to traverse the vanes in the manner just described. The steam which enters the small reinjection chamber C 45 traverses the same and returns to the rotor R', again impacting against the vanes V', etc. It then continues around the rotor, passing into the chambers C' next in advance, traverses the same and returns to the 50 vanes V', etc. This action of the steam continues throughout the several chambers C and C' until all of the steam finally exhausts out of the ports E and E'.

In this form of the turbine, when operating in clockwise or reverse direction, a small proportion of the steam emerging from nozzle 15 may have a tendency to exhaust through the adjacent internal channel C', but because of the direction in which the 55 steam is forced into the chamber formed between the rotor and the stator, almost all of the steam will thus be prevented from being diverted into said channel C', since because of the close proximity of the entrance 60 to this channel C' to the discharge end of the

nozzle 15, the steam would have to make a very sharp turn in order to enter this channel, and therefore, while, as above stated, some steam will tend to escape through this channel, the larger part of the steam will 70 follow the lines of least resistance, which will be in the general direction of rotation of the rotor. In practical use, it is not necessary that the rotor shall develop the same power in the reverse direction as it does 75 when rotating forward, and therefore the loss of steam because of the channels C' would not be material.

It will be manifest from the foregoing that a very efficient turbine is obtained, inasmuch as the steam is reinjected at intervals 80 by the chambers C and C' to appreciably increase the action of the steam.

Referring now to Figs. 8, 9, and 10, I have here shown one means for controlling and 85 actuating two or more reversible turbine engines of the type wherein the steam or other motive fluid traverses the entire rotor in either direction before exhausting. As shown in Figs. 8 and 9, T and T' designate 90 two turbines, of the type above referred to, which are connected in series for movement in either direction by means of pipes P', P², P³, and P⁴, through nozzles N and N'. Steam is supplied to and exhausted from 95 each turbine T and T' by means of pipes H and H', the pipes H, P³ and H', P' constituting pairs, the individual pipes of each pair entering the casing of turbine T at right angles to each other and being in communication at the nozzles N and N' respectively. The same is true of the pipes H, P² and H', P⁴ of turbine T'. The pipes H and H' for turbine T are connected at their confronting ends by a steam supply pipe K, 100 which is connected to any suitable source of supply, while the pipes for turbine T' are provided at their meeting ends with a common exhaust pipe L. The pipes P', P², P³ and P⁴ and H and H' are controlled by cocks 105 O, O', etc., and these cocks in turn are controlled by a common shaft M. The location and function of the cocks O, O', etc., will be understood from a consideration of the operation of the entire mechanism. The shaft M is operatively connected to each cock O by means of worms G, fixed to the shaft M and meshing with worm gears G' fixed to the stems of the cocks O.

By such an arrangement, all of the valves 120 can be simultaneously moved to open or closed position, or vice versa, according as the shaft M is rotated in one direction or the other. Fixed to the opposite ends of the shaft M are wheels W which carry handles 125 Y for manipulating the shaft from either end, as will be understood.

Referring now to Fig. 10, I have here shown means for controlling the nozzles N and N' so that, when one is serving as an 130

inlet and the other as an exhaust, the area of the inlet nozzle will be restricted sufficiently to produce a fine jet of steam for effectively propelling the turbine, while the exhaust nozzle is correspondingly enlarged to permit the free and unrestricted exhaust of the steam. To obtain this end, I have, in the present instance, provided valves n and n' for the nozzles N and N' , each of which is in the form of a blade coextensive in length with the nozzle, and fixed to a pintle n^2 for swinging movement. The valves n and n' are simultaneously actuated by the shaft M through the medium of gears Z , fixed to shaft M as shown in Fig. 10 and on the pintles n^2 , around which an endless chain n^3 is trained.

The operation of the mechanism is as follows:

When it is desired to rotate the turbines T and T' in the direction of the arrows in Fig. 9, the shaft M occupies the position shown in Fig. 8, wherein the valves O , O' , O^2 and O^3 are open and the valves O^4 , O^5 , O^6 , and O^7 are closed, while valves n and n' occupy the reverse positions to those shown in Fig. 10. With the valves O in these positions, steam from pipe K is admitted to pipe H for turbine T , passing into the turbine through nozzle N and exhausting through nozzle N' . It then enters the pipe P' , passes to pipe P^2 , and enters the turbine T' through nozzle N . After traversing turbine T' , the steam exhausts through nozzle N' and enters pipe H' of turbine T' and exhausts to the atmosphere through pipe L . When rotating the turbines in the opposite direction, the shaft M is rotated sufficiently to cause valves O to O^7 to assume reverse positions, while the blades n and n' are caused to assume the positions shown in Fig. 10. With all of the valves occupying the reverse positions, steam from pipe K enters pipe H' of turbine T passing through nozzle N' to turbine T' . It then traverses turbine T exhausting through nozzle N into pipe P^3 . From pipe P^3 it enters pipe P^4 , traversing such pipe and entering turbine T' , through nozzle N' , around the turbine and out through nozzle N into pipe H , exhausting to atmosphere through pipe L .

From the foregoing description it will be manifest that I have provided a simple and efficient means for controlling the supply of steam to two turbines connected in series for effecting the reversal of each turbine simultaneously, and that the nozzles for each turbine are automatically restricted or enlarged according as the steam travels in one direction or the other through such turbines. Although I have shown and described means for controlling only two turbines, it is obvious that any number of turbines may be similarly controlled by multiplying the controlling means.

Referring now to Fig. 13, I have here shown a turbine T^2 which is a modification of turbine T' , and is identical to the same with the exception that the stator S^2 is not formed with the reinjection chamber, and the inner wall t^2 thereof is tapered from one inlet nozzle 15 to the corresponding exhaust E or E' , to provide a stator, the inner surface of which is eccentric. The purpose of the eccentric stator is to provide spaces between the rotor R^2 and the stator S^2 which increase from each inlet nozzle 15 to the corresponding exhaust so that, during forward movement of the rotor, the steam entering the nozzles is permitted to expand whereby the energy of the steam is more fully utilized than in turbines of the ordinary construction.

When the rotor R^2 moves in the reverse direction, the eccentric formation of the stator S^2 does not assist in utilizing the expansive force of the steam, as will be obvious. However, in the particular use for which a turbine of this character is adapted, it is not necessary to secure the same power in the reverse movement as in the forward movement of the rotor.

Although I have herein shown and described only three forms of turbines and one form of controlling means embodying my invention, it is to be understood that various changes and modifications may be made without departing from the spirit of the invention, and the spirit and scope of the appended claims.

What I claim is:

1. A reversible turbine engine comprising a stator, a rotor in the stator, an inner circular series of radially disposed vanes formed on said rotor, said vanes being spaced apart and connected by arcuate curved portions, a second set of radially disposed vanes surrounding the first set, the vanes of the second set having one side thereof curved toward their inner ends, the vanes of the inner set being arranged in alternate relation to the vanes of the outer set, and means for introducing a motive fluid radially of the rotor to effect rotation of said rotor in either direction.

2. A reversible turbine engine comprising a stator, and a rotor having an inner set and outer set of radially disposed vanes, the outer set being arranged in alternate relation to the inner set, and lubricating means carried by the vanes of the outer set for lubricating the contacting surfaces of the rotor and the stator.

3. A turbine comprising a rotor including an inner series of vanes, an outer series of vanes, and an intermediate series of vanes arranged in staggered relation to the inner and outer series and tapering from their inner ends to their outer ends, and a stator enveloping said rotor.
